UNITED STATES PATENT OFFICE.

RALPH H. WEST, OF CLEVELAND, OHIO.

MOLD FOR CASTING CHILLED ROLLS.

No. 894,926.

Specification of Letters Patent.

Patented Aug. 4, 1908.

Application filed February 11, 1907. Serial No. 356,856.

To all whom it may concern:

Be it known that I, RALPH H. WEST, a citizen of the United States of America, residing at Cleveland, in the county of 5 Cuyahoga and State of Ohio, have invented certain new and useful Improvements in Molds for Casting Chilled Rolls; and I hereby declare the following to be a full, clear, and exact description of the invention, 10 such as will enable others skilled in the art to which it pertains to make and use the same.

This invention relates to improvements in molds for casting chilled rolls.

15 The primary object of this invention is to provide a roll-casting mold which is beneficial in the manufacture of a chilled roll for obtaining a casting which has all the requirements essential for the production of a 20 chilled roll in which the chilled peripheral shell or crust of the roll-body is uniform in thickness circumferentially and from end to end of the roll, free from checks or cracks 25 and other imperfections and found to be perfectly round when put in a lathe to be turned.

With this object in view, and to the end of realizing other advantages hereinafter appearing, my invention consists, first, in the provision not only of an upper mold-part or cope which is arranged and adapted to be lowered within the upper end of the central part or chill of the mold, but in the provision of a partition-forming head which 35 forms a support for the loam or molding sand forming the surrounding wall or walls and bottom of the roll-neck-forming cavity of the drag and can be lowered to accommodate a descent of the casting while the 40 chill and the drag-casing remain stationary and is supported by a body of loose sand or similarly fluent or readily displaceable material which is contained within the said casing between the said head and a perforated bottom with which the said casing is 45 provided under the said loose material, with the perforations in the said bottom arranged to discharge downwardly, and with the passage of the said loose material through 50 the said bottom controlled by a suitably applied and suitably operated and normally closed valve so that when the said valve is opened the said loose material will gravitate through the aforesaid perforations and permit 55 the casting and the aforesaid head and any movable portion of the drag between

the said head and the casting to descend; second, to provide means whereby the descent of the said movable portion of the drag is indicated externally of the drag- 60 casing and the loose sand or fluent material discharged through the aforesaid bottom may be weighed so as to disclose externally of the mold the weight or measure of the material which passes through the said bottom during the operation of the mold; third, to provide means whereby the aforesaid valve may be conveniently operated from the upper end of the mold; fourth, to provide an annular chill which is not only composed of superimposed rings, but which is provided internally with downwardly and inwardly sloping seat-forming surfaces arranged at different elevations respectively and extending circumferentially of the chill, 70 which seat-forming surfaces have such relative arrangement and dimensions to not only adapt them to center and support the roll-body-forming portion of the casting but to accommodate a gradual increase in the 75 horizontal contraction of the casting toward the upper end of the chill and permit of parallelism of the said seat-forming surfaces; fifth, to form the lower end of the chill and the lowermost seat-forming surface 80 of the chill in one solid piece which is integral with the adjacent portion of the drag-casing; sixth, to provide not only a simple and efficient cut-off for interrupting continuity in the runner-gate or passage-way 85 employed in conducting molten metal to the drag-cavity but in supporting the said cut-off as required to render it movable downwardly with the descent of the aforesaid downwardly movable portion of the drag, 90 and seventh, to attain other advantages 95 which may hereinafter appear.

In the accompanying drawings, Figure 1 is a side elevation, largely in central vertical section, of a roll-casting mold embodying my 100 invention, and in this figure the mold is shown within a pit. Figs. 2, 3 and 4 are horizontal sections on line 2—2, line 3—3 and line 4—4, respectively, Fig. 1, looking downwardly. Fig. 5 is a vertical section on 105 line 5—5, Fig. 1, looking inwardly. Figs. 6, 7 and 8 are horizontal sections on line 6—6, line 7—7 and line 8—8, respectively, Fig. 1, looking downwardly. Fig. 9 is a vertical section on line 9—9, Fig. 1, looking in the direction indicated by the arrow. Fig. 10 is a horizontal section on line 10—10, Fig. 1,

looking upwardly. Fig. 11 is a vertical section on line 11—11, Fig. 1, looking in the direction indicated by the arrow, except that in Fig. 11 the valve d is shown open whereas in Fig. 1 the valve is shown closed.

My improved roll-casting mold (see Fig. 1) comprises a lower mold-part or drag A, a central mold-part or chill B, and an upper mold-part or cope C. The chill B (see Figs. 1, 3 and 4) is stationary, being supported as will hereinafter appear. The chill B is annular and arranged vertically, having a circular roll-body-forming chamber b extending from end to end of the chill. The upper mold-part or cope C, (see Figs. 1 and 2) is provided centrally with a chamber 13 which extends vertically through the cope and is arranged centrally of the upper end of and in communication with the chill-chamber b . The cope C depends into and snugly but slidably fits within the upper end of the chill. The cope C is supported from the chill as required to render the cope capable of being lowered within the chill, as will hereinafter appear.

The drag A (see Figs. 1, 6, 7 and 9) is provided with a cavity a which is arranged centrally of the drag and extends downwardly from the upper end of the drag a suitable distance. The cavity a is arranged centrally of the lower end of and in communication with the chill-chamber b . The body of the roll to be produced is cast in the chill B, whereas the necks of the rolls are cast in the drag and cope. The drag-cavity a and the cope-chamber 13 are of course enough smaller diametrically than the chill-chamber b and have the general outline required to form the necks of the roll to be cast.

The surrounding wall or walls of the upper portion of the drag-cavity a (see Figs. 1 and 6) are composed of a body of loam or molding sand a' , which body is surrounded by and supported from a metal ring a^2 which slidably fits internally of and is movable vertically within the upper portion of a stationary metal casing E known as the drag-casing. The ring a^2 is detachably secured to the upper portion of the drag-casing E by endwise shiftable horizontally arranged pins a^3 which are spaced circumferentially of and have bearing in the said casing and extend into the said ring. The pins a^3 are withdrawable endwise from the ring a^2 to detach the ring from the drag-casing E and permit the said ring and the body of loam or molding sand borne thereby to descend, as will hereinafter appear, with the body of loam or molding sand A' which (see Figs. 1, 7, 8 and 9) forms the surrounding wall or walls of the lower portion and bottom of the cavity a . The body A' abuts against the lower end of the body a' and rests upon and is supported from a head F which slidably fits internally of and is movable vertically within the lower portion of the drag-casing E. The head F is

provided at its upper side with an upwardly projecting flange F' which extends circumferentially of the body of loam or sand A'. The flange F' affords a bottom bearing to the ring a^2 during the descent of the members F, 70 A', a' and a^2 as will hereinafter appear. It will be observed therefore that the superimposed bodies of loam or molding sand a and A' constitute a downwardly movable inner portion of the drag; that the said downwardly movable portion of the drag is provided with the drag-cavity, and that the ring a^2 and the head F and its flange F' form a casing for the said superimposed bodies and obviously also form members of the downwardly movable portion of the drag. The flange F' is provided with a laterally and outwardly projecting arm f' which is formed preferably by a horizontally arranged pin which extends into and is borne by the said flange and projects from the said flange into and through a vertically arranged slot E' formed in the drag-casing E, which slot extends far enough below the said pin or arm to accommodate the descent or downward travel of the head F.

It will be observed that the arm or projecting member f' of the head F projects externally of the drag-casing where it can be readily observed, and obviously a downward movement of the said arm during the operation of the mold is indicative of the descent of the downwardly movable portion of the drag.

The head F rests upon a body of loose sand or similarly readily displaceable or fluent material f , which (see Fig. 1) is contained within the casing E and below the head F, and the head F forms a partition between the body of material f and the lower of the superimposed bodies a' and A' of loam or molding sand.

The drag-casing E has a perforated bottom e which is instrumental in supporting the body of loose and fluent material f .

The bottom e (see Fig. 1) is provided in its upper side with an upwardly flaring cavity e' having a flat bottom e^2 arranged centrally of the cavity and an upwardly flaring surrounding wall. The bottom e 115 (see Figs. 1, 10 and 11) is provided centrally with a circular hole e^3 extending vertically through the bottom. The bottom e is also provided with several downwardly discharging slots or perforations e^4 arranged radially of the bottom and spaced equidistantly from and circumferentially of the hole e^3 , and a rotary valve d is arranged over the cavity-bottom e^2 and consists of a circular conical member which covers the said cavity-bottom and is provided at its under side and centrally with a depending circular lug d' which engages and is turnable within the hole e^3 . The valve d is provided with several vertical slots or perforations d^4 arranged 130

radially of the valve and spaced equidistantly from and circumferentially of the axis of the valve, which perforations are arranged in or out of registry with the perforations e^4 in the bottom e according as the valve is in its open or closed position. In Fig. 1 the valve d is shown in its normal position with its perforations d^4 out of registry with the perforations e^4 in the bottom e and consequently closed, whereas in Fig. 11 the valve is shown open with its perforations d^4 in registry with the perforations e^4 . The conical form of the valve and the upwardly flaring surrounding wall of the cavity e' in the bottom e facilitate the descent of material f to the perforations e^4 in the bottom e when the valve d is actuated into its open position as required to bring the perforations in the valve into registry with the aforesaid perforations in the said bottom and thereby permit the discharge of the said material downwardly through the said perforations so as to accommodate the descent of the head F and bodies of loam or molding sand a' and A' to permit the casting to lower during the cooling of the casting.

The depending lug d^3 of the valve d (see Figs. 1 and 10) is provided with a laterally and outwardly projecting lever-forming arm d' and the bottom e is recessed in its under side, as at e^5 to accommodate the location of the said arm or lever, but the said bottom preferably has a portion e^6 thereof extending around and thereby affording bearing to the said lever.

The drag-casing E (see Fig. 1) is provided externally and a suitable distance above the outer end of the lever d' with a laterally and outwardly projecting bracket 16 to which a lever G is horizontally fulcrumed, as at G' . The lever G extends upwardly to the upper end of the mold and a suitable distance above the upper end of the pit P where the said lever can be conveniently operated. The lever G (see Figs. 1 and 10) straddles or depends alongside of the outer end-portion of the lever d' of the valve d and is consequently arranged to actuate the said valve-lever as required to turn the valve to the extent necessary to place the perforations d^4 in the valve into registry with the perforations e^4 in the bottom e and thereby open the valve.

To prevent accidental operation of the lever G an endwise shiftable pin g extends loosely through the upper end of the lever into a bracket 17 which is suitably supported and projects upwardly from the surrounding wall of the pit P , which pin engages a hole 18 in the said bracket in the closed position of the valve and thereby locks the lever in the said position of the valve but is withdrawable endwise from the bracket to unlock the lever preparatory to the actuation of the valve into its open position.

A suitably supported receptacle I (see

Figs. 1 and 11) is arranged under the drag-casing-bottom e in position to receive material discharged downwardly through the perforations e^4 . The receptacle I is provided with two trunnions I' and I' arranged horizontally and in line endwise at opposite sides respectively of the receptacle and having bearing in upright arms J' of a lever J which is arranged to tilt in a vertical plane and mounted or fulcrumed upon a knife-edge 20 arranged centrally between the ends of the lever, and two knife-edges 22 and 23 are arranged under opposite ends respectively of the lever J in position to limit the actuation of the lever in opposite directions respectively. The receptacle I is arranged at one side of the fulcrum of the lever J , and a vertically arranged rod J^2 is mounted and arranged to bear downwardly upon the lever J at the outer side of the fulcrum and extends loosely through and has lateral bearing in two vertically spaced brackets 24 which are rigid with the surrounding wall of the pit P . The rod J^2 extends to and above the upper end of the pit and is provided near its upper end and externally with a shoulder or seat J^3 for supporting weights (not shown) employed in weighing the contents of the receptacle I . It will be observed therefore that the weight or measure of the said contents is conveniently indicated at the upper end of the pit.

The drag-cavity a is provided at one side and a suitable distance below the upper end of the cavity (see Figs. 1, 7 and 9) with an inlet for molten metal, and the mold is poured through the said inlet which is formed by the discharging end of a runner-gate which (see Fig. 1) has an upright portion A^3 and a lower portion A^2 which extends horizontally and laterally from the lower end of the upright portion through the drag-casing E and at its inner discharging end forms the inlet of the cavity a . The lower and laterally extending portion A^2 of the runner-gate has its inner end-portion shown formed in the upper end of the body of loam or molding sand A' , and has its outer end-portion surrounded by a casing E^2 which is formed on the drag-casing E and also surrounds the lower end of the upright portion A^3 of the runner-gate, which upright portion is surrounded above the casing E^2 by a casing E^3 which rests upon and is suitably attached to the casing E^2 .

The lower or inner end-portion of the cope-chamber 13, (see Fig. 1) has the outline and the dimensions required to form the inner end-portion of a roll-neck between the outer end portion of the said neck and the body of the roll, and the surrounding wall or walls of the said portion of the cope-chamber are formed by a body of loam or molding sand 14 built up within and surrounded by and supported in any approved manner from a metal casing K which constitutes the lower section of the cope-casing, and the remainder of the cope-

chamber has the contour and dimensions required to form the wobble-forming outer end-portion of the said neck and to form a feeding-head *h* above the wobble-casting portion 5 of the said chamber, with the surrounding wall or walls of the feeding head and the wobble-casting portion of the cope-chamber built up of a body of loam or molding sand 15 within and surrounded by and supported in 10 any approved manner from a metal casing *k* which constitutes the upper section of the cope-casing. The casing-section *k* is seated on but removable from the top of the lower section *K* of the cope-casing. It will be 15 observed therefore that the cope comprises an upper part which consists of the casing-section *k* and body of loam or molding sand 15 and a lower part which consists of the casing-section *K* and body of loam or mold- 20 ing sand 14.

The upper cope-casing-section *k* (see Figs. 1 and 2) is provided at its lower end and externally with laterally projecting lugs *k'* spaced circumferentially of the said cope-casing-section. Through each lug *k'* extends a screw *k''* which is arranged with its head abutting against the upper side of the said lug, which screw has its threaded shank screwed into the flange *K'*. Obviously therefore the upper cope-casing-section is detachably secured to the lower cope-casing-section, and only the withdrawal of the screws *k''* is required to accommodate the separation of the upper cope-part from the lower cope- 35 part.

The lower cope-casing-section and consequently the cope are supported from the chill as will hereinafter appear.

The chill *B* (see Figs. 1, 3 and 4) is composed of superimposed rings arranged in line vertically, and the lowermost ring 25 of the lower portion of the chill is solid and formed integral with the adjacent portion of the drag-casing *E*, and the remainder of the 40 lower portion of the chill is formed by superimposed sectional rings 26 which are divided vertically into sections, having their joints 27 spaced circumferentially of the chill. Each section of the lower of adjacent rings of the 45 said lower portion of the chill is provided at the top with a rib 28 having beveled sides and arranged circumferentially of the chill, which rib engages a correspondingly shaped recess 30 formed in and extending circumferentially of the bottom of the upper of the 50 said rings. By this construction the sections of the upper of adjacent rings of the lower portion of the chill are held in place upon the lower of the said rings.

60 The uppermost sectional ring of the lower portion of the chill is reduced in external diameter at its upper end, as at 32, Fig. 1, and the said diametrically reduced upper end of the said ring is embraced by the lower end 65 of the upper portion of the chill, and the said

upper portion of the chill (see Figs. 1 and 3) is shown formed by a single ring 33 which is comparatively long and divided into halves or sections, with the adjacent ends of adjacent sections provided with laterally and outwardly projecting flanges 34 and held properly joined together in any approved manner, as, for instance, by tapering pins 35 which engage registering holes 36 formed in the said flanges. 75

To more effectually and positively hold the upper portion 33 of the chill in place upon the uppermost chill-ring 26 of the lower portion of the chill, wedges *Q* are arranged externally of the lower end of each section 80 of the aforesaid upper portion 33 of the chill and driven tightly into place between the said section and lugs 39 which are formed on the adjacent section of the said uppermost chill-ring 26 of the lower portion of the chill and project laterally and upwardly from the said chill-ring a suitable distance. The chill-rings are also shown provided externally (see Fig. 1) with recesses 37 adapted to be engaged by clamps (not shown) well known 85 in foundry practice for detachably securing mold-sections together.

The chill *B* is supported from the drag-casing *A* as already indicated, and as the lowermost and solid chill-ring is arranged 95 concentrically relative to the drag-cavity *a* it is obvious that the remainder of the chill which is built up upon and concentric relative to the said solid ring is accurately centered relative to the said cavity. 100

By the construction hereinbefore described it will be observed that each chill-ring, save the lowermost and solid chill-ring, rests on and is held to the next lower chill-ring, and that the sections of the upper of adjacent 105 chill-rings snugly embrace at their lower ends the upper ends of and rest on the sections of the lower of the said rings. It will be observed therefore that the chill-rings are effectively locked together and to the drag-casing when upward displacement in any approved manner of the uppermost or top ring is prevented. 110

The chill *B* (see Fig. 1) is provided internally with downwardly and inwardly sloping 115 seat-forming surfaces 40 extending circumferentially of the chill and arranged at different elevations respectively. The seat-forming surfaces 40 are parallel and preferably correspond in size diametrically at their 120 upper extremities. That is, the upper extremities of the seat-forming surfaces 40 are shown arranged in the same plane vertically. The upper of adjacent seat-forming surfaces 40 is longer vertically or longitudinally of 125 the chill than the lower of the said surfaces so that the lower end of the lower of adjacent seat-forming surfaces is larger diametrically than the lower end of the upper of the said surfaces, and consequently the chill-chamber 130

b is larger diametrically at the lower extremity of the lower of adjacent seat-forming surfaces than at the lower extremity of the upper of the said surfaces. A sloping seat-forming surface 40 is formed internally of each ring 26 of the lower portion of the chill, and obviously by the construction hereinbefore described the upper of adjacent rings of the said lower portion of the chill forms a larger portion vertically of the chill-chamber than the lower of the said rings.

It will be observed that several seat-forming surfaces 40 are formed in the comparatively long ring 33 which forms the upper portion of the chill.

By the construction hereinbefore described it will be observed that the sloping seat-forming surfaces 40 of the chill are spaced farther apart toward the upper end of the chill; that each of the said surfaces is formed upon a rib-forming portion *b'* of the chill; that the chill is therefore provided with ribs *b'* which extend circumferentially of the chill-chamber *b* and are arranged at different elevations respectively; that each rib *b'* is provided with a downwardly and inwardly sloping seat-forming surface 40 extending circumferentially of the chamber, and that the upper of adjacent ribs *b'* is larger in dimensions laterally and longitudinally of the chill than the lower of the said ribs.

I would here remark that the horizontal contraction of the roll-body-forming portion of the casting gradually increases toward the upper end of the chill, and obvious therefore is the importance of the hereinbefore described relative dimensions and arrangement of the sloping seat-forming surfaces 40 when parallelism of the said seat-forming surfaces for convenience and economy of construction is to be maintained.

By the hereinbefore described relative arrangement and dimensions of the seat-forming surfaces 40, notwithstanding that the said surfaces are parallel, the contracting casting is accurately centered relative to and from end to end of the chill by the said seat-forming surfaces during any lowering of the casting while the casting is cooling or contracting.

In casting a roll by my improved mold the peripheral crust or shell of the casting formed in and by the chill is during its contraction maintained in a strictly central position relative to the chill and supported circumferentially of and upon the sloping seat-forming surfaces 40 at different elevations respectively. The casting is supported at as many intervals vertically as there are seat-forming surfaces 40 so that the said shell or crust is not liable to be cracked or put out of round or rendered defective by the pressure of molten metal within and centrally of the casting.

The lower cope-casing-section K, and consequently the cope, (see Figs. 1 and 2) are

adjustable vertically as will hereinafter appear, and, as already indicated, supported from the chill.

The flange K' (see Figs. 1 and 2) of the said cope-casing-section K overhangs lugs 38 which are formed on and externally and spaced circumferentially of the upper end of the chill.

The means for supporting the cope from the chill is shown to consist of several screws 75 *l* which are arranged vertically and engage the upper end of the chill, resting upon the chill and engaging correspondingly screw-threaded holes formed in the flange K' of the lower cope-casing-section K and instrumental in preventing upward displacement of the upper portion of the chill when the cope, as shown, is attached to the chill in any approved manner, as, for instance, by bolts R and nuts *r*.

Through each lug 38 loosely extends a bolt R whose shank extends also and loosely through and a suitable distance above the flange K'. The said bolt R is arranged with its head under the said lug. A correspondingly screw-threaded nut *r* is mounted on the shank of the bolt above the said flange, and washers *t* are interposed between the flange K' and the nuts *r*. The bolts R, nuts *r* and washers *t* constitute means for preventing upward displacement of the cope.

Obviously the cope can be lowered or adjusted vertically relative to the chill by a proper manipulation of the screws *l* and nuts *r*.

Preparatory to any lowering of the casting during the operation of the mold continuity in the laterally extending portion A² of the runner-gate is interrupted at the interior of the drag-casing E by a suitably operated cut-off *u* which (see Figs. 7, 8 and 9) is shown borne by the flange F' of the head F. Preferably the flange F' is provided externally of its upper portion with a guideway 42 which extends a suitable distance circumferentially of the flange from the laterally extending portion A² of the runner-gate to a slot 43 formed in the drag-casing E, and the cut-off *u* consists of a metal plate which engages the said guideway and is seated upon the bottom wall 100 of the said guideway. Normally the cut-off is arranged at one side of the laterally extending portion A² of the runner-gate, as shown very clearly in Figs. 7, 8 and 9 but is actuated at the proper time and in any approved manner circumferentially of the flange F' and into position interrupting continuity in the said portion of the runner-gate so as to separate any molten metal within the said portion of the runner-gate where the latter extends into 105 the body of loam or sand A' from any metal in the runner-gate where the latter is stationary and arranged externally of the vertically movable contents of the drag-casing E. It

will be observed therefore that the cut-off *u* is 110 115 120 125 130

adapted to be lowered with the downwardly movable portion of the drag, and the slot 43, which is formed in the drag-casing to afford access to the guideway 42 and consequently to the cut-off, extends far enough circumferentially of the casing to accommodate the insertion into the said guideway of a tool or instrument (not shown) suitable for use in actuating the cut-off from its normal and inoperative position into its operative and runner-gate-obstructing position.

The chill B (see Fig. 1) is provided in one of the rings of its lower portion with a horizontally arranged hole 45 which extends laterally from the interior to the exterior of the chill. A correspondingly arranged endwise shiftable bar or member x engages the hole 45 and is movable inwardly. The member x extends a suitable distance outwardly beyond the exterior of the chill and has a beveled inner end arranged flush in the outer and normal position of the member x with the seat-forming surface 40 formed internally of the said ring. The member x is provided next externally of the chill with a screw-threaded portion x' , and a nut x^2 is mounted on the said screw-threaded portion and forms an adjustable stop for limiting the inward movement of the said member x .

The outer end of the nut x^2 forms a laterally and outwardly facing shoulder on the member x , and an upright lever m (see Figs. 1 and 5) overlaps the said shoulder and is arranged to actuate the said member x inwardly against the action of a suitably applied spiral spring w . The lever m extends upwardly to the upper end of the mold and is suitably fulcrumed, as at m' , a short distance above the member x to a bracket n which projects laterally and outwardly from and is rigid with the chill-ring through which the said member x extends. The bracket n is provided at its outer end with a depending arm n' which affords bearing to the member x . The member x extends outwardly through and a suitable distance beyond the bracket-arm n' , and a nut x^3 is mounted on the outer end of the said member x , and the spring w is preferably mounted and confined on the member x between the said nut and the bracket-arm and automatically acts to retain the said member x in its outer position.

Means for preventing turning of the endwise shiftable bar or member x is provided and preferably comprises a lug x^4 formed on the free end of the said member x and projecting into an enlargement 41 of the inner end of the hole 45.

The lever m (see Figs. 1 and 2) overlaps a lug 46 formed on the cope-casing-flange K' in the outer and normal position of the member x . An endwise shiftable pin 47, which has bearing in the lever m , engages a hole 48 formed in the said lug and thereby locks the lever in the outer position of the

member x . It will be observed therefore that the provision of the pin 47 within the lug 46 locks the member x in its outer position against the action of the spring w , and that a removal of the said pin from the lug 46 renders the spring free to actuate the said member x as far as the engagement of the adjustable stop x^2 with the lever m will permit. The lever m , when it is unlocked by the withdrawal of the pin 47, is actuated in the direction required to move the member x inwardly against the action of the spring w by the action of a weight y with which the lever is provided at the outer side but above the fulcrum of the lever, but of course the lever and consequently the member x are not unlocked until after the formation of the desired crust or shell of the roll-body-forming portion of the casting during the operation of the mold has progressed far enough.

Briefly described the operation of my improved mold is as follows:—By manipulating the screws l and nuts r the cope is properly adjusted relative to the chill whereupon the molten metal employed in casting a roll is introduced through the runner-gate to the drag-cavity a , filling the said cavity and then rising into and filling the chill and then rising into and within the cope-chamber 13 until the level of the molten metal within the cope-chamber has risen as far as the upper end of the lower cope-part. The upper cope-part is preferably kept off the mold preparatory to the pouring of the mold so that the operators or attendants can skim off any dirt or dross appearing at the level of the molten metal when the said level rises to the upper end of the lower cope-part. When the molten metal has had all the dross and dirt skimmed therefrom and the fed metal has settled down from the lower cope-part to nearly fully feed the chill the upper cope-part is placed and fastened in position upon the lower cope-part, and molten metal is then poured into the feeding head from above to supply the cope after which by the use of a feeding rod worked up and down round the wobble-forming portion and inner end or main portion of the roll-neck to be cast within the cope a good union of the metal below the wobble and the metal introduced from above is effected. The cut-off u is of course actuated into its runner-gate-obstructing or operative position as soon as the mold is poured. The molten metal introduced into the mold is permitted to stand until it shall have formed a suitable shell or crust in the chill whereupon the cope and the head F are lowered, the cope being lowered by a proper manipulation of the screws l and nuts r , and the head F being lowered upon unlocking and thereupon manipulating the lever G as required to open the valve d and

permit the flow of loose material *f* through the perforated bottom *e* into the receptacle *I*, but before pouring the mold or preparatory to permitting the head *F* to descend 5 the ring *a*² which bears the upper of the superimposed bodies of loam or molding sand of the drag is unlocked by withdrawing the pins *a*³ from the said ring so as to permit the said ring and its body of loam 10 or molding sand to lower with the body of loam or molding sand *A*'. Obviously the casting and the bodies of loam or molding sand which form the drag-cavity *a* descend by gravity or by gravity with the assistance 15 of downward pressure exerted downwardly on the cope and consequently downwardly on the roll-body-forming portion of the casting by a proper manipulation of the screws *l* and nuts *r*. By lowering the casting 20 during the operation of the mold the beads or ribs which are formed on and externally of the crust or shell of the roll-body-forming portion of the casting and next over the seat-forming surfaces 25 of the chill-rings are kept in contact with the said seat-forming surfaces during the operation of the mold. If pressure is to be exerted downwardly upon the upper end of the roll-body-forming metal to form a good 30 union between the upper neck and the roll-body, or for other reasons, the cope is lowered independently of the remaining portions of the mold by a proper manipulation of the screws *l* and nuts *r* without permitting 35 the descent of the casting during the exertion of pressure downwardly upon the upper end of the roll-body-forming portion of the casting. When the peripheral crust or shell of the roll-body-forming portion 40 of the casting has formed or progressed far enough in the chill the member *x* is unlocked and thereby rendered free to move into the chill to ascertain the amount of horizontal contraction of the roll-body-forming portion 45 of the casting.

In removing the casting from the mold the cope is of course first removed, whereupon the chill-rings are readily removed one at a time and in order.

50 What I claim is:—

1. In a mold for casting a chilled roll, a vertically arranged annular chill provided internally with downwardly and inwardly sloping seat-forming surfaces arranged at 55 different elevations respectively and extending circumferentially of the chill, and the upper of adjacent seat-forming surfaces being smaller diametrically at its lower extremity than the lower of the said surfaces so that 60 the chamber of the chill is larger diametrically at the lower extremity of the lower of adjacent seat-forming surfaces than at the lower extremity of the upper of the said surfaces.

2. In a roll-casting mold, a vertically arranged annular chill provided internally with 65

correspondingly downwardly and inwardly sloping parallel seat-forming surfaces arranged at different elevations respectively and extending circumferentially of the chill, said seat-forming surfaces corresponding 70 diametrically at their upper ends, and the upper of adjacent seat-forming surfaces being smaller diametrically at its lower extremity than the lower of the said surfaces so that the chamber of the chill is larger diametrically 75 at the lower extremity of the lower of adjacent seat-forming surfaces than at the lower extremity of the upper of the said surfaces.

3. In a roll-casting mold, an upright chill having a circular chamber and provided internally with parallel downwardly and inwardly sloping seat-forming surfaces arranged at different elevations respectively and extending circumferentially of the chamber, and the upper of adjacent seat-forming 85 surfaces being longer vertically of the chill and extending farther inwardly than the lower of the said surfaces.

4. In a roll-casting mold, an upright chill having an internal chamber which extends 90 from end to end of the chill, and provided internally with downwardly and inwardly sloping seat-forming surfaces arranged at different elevations respectively and extending circumferentially of the chamber, and the 95 lower ends of the said seat-forming surfaces being spaced farther apart toward the upper end of the chill, and the upper of adjacent seat-forming surfaces being smaller diametrically at its lower extremity than the lower of the said surfaces so that the chamber of the chill is larger diametrically at the lower extremity of the lower of adjacent seat-forming surfaces than at the lower extremity of the upper of the said surfaces.

5. In a roll-casting mold, an upright chill having a circular chamber which extends from end to end of the chill, and provided internally with downwardly and inwardly sloping seat-forming surfaces arranged at 110 different elevations respectively and extending circumferentially of the chamber, and the upper of adjacent seat-forming surfaces being smaller diametrically at its lower extremity but larger in dimensions vertically 115 than the lower of the said surfaces.

6. In a roll-casting mold, a vertically arranged chill having its lower portion composed of superimposed rings which are arranged in line vertically and, except the 120 lowermost ring, divided vertically into sections, with the lower of adjacent rings of the said portion of the chill provided at the top with a rib extending circumferentially of the chill and projecting into and overlapped on 125 both sides by the upper of the said rings, and the uppermost of the said rings being embraced by the upper portion of the chill, and each of the said rings and the upper portion of the chill being provided internally with 130

suitably sloping seat-forming surfaces having such relative arrangement and dimensions that the casting produced in the mold during the operation of the mold shall during its contraction rest entirely upon the said seat-forming surfaces.

7. In a roll-casting mold, a vertically arranged chill having its lower portion composed of superimposed rings which are arranged in line vertically and provided internally with downwardly and inwardly sloping seat-forming surfaces extending circumferentially of the chill, said chill having its upper portion composed of a comparatively long ring divided vertically into sections and provided internally with a plurality of downwardly and inwardly sloping seat-forming surfaces extending circumferentially of the chill, and the last-mentioned seat-forming surfaces and the first-mentioned seat-forming surfaces having such relative arrangement and dimensions that the casting produced in the mold during the operation of the mold shall during its construction have bearing upon the said seat-forming surfaces.

8. In a roll-casting mold, a vertically arranged chill having its lower portion composed of superimposed rings which are arranged in line vertically and provided internally with suitably sloping seat-forming surfaces extending circumferentially of the chill, said chill having its upper portion composed of a comparatively long ring divided vertically into sections and provided internally with a plurality of suitably sloping seat-forming surfaces extending circumferentially of the chill, said sections of the last-mentioned ring being suitably held in place, and the lower of adjacent rings of the chill being embraced at its upper end by the lower end of the upper of the said rings.

9. In a roll-casting mold, a vertically arranged chill having its lower portion composed of superimposed rings and having all the rings above the lowermost ring divided vertically into sections, with the sections of the uppermost ring suitably held in place, and with the sections of the lower of adjacent sectional rings embraced at their upper ends by the lower end of the upper of the said rings; and the said rings being provided internally with parallel downwardly and inwardly sloping seat-forming surfaces extending circumferentially of the chill, with the seat-forming surface in the upper of adjacent rings smaller diametrically at its lower extremity than the seat-forming surface in the lower of the said rings.

10. In a roll-casting mold, an upright chill having a circular chamber which extends from end to end of the chill and provided internally with ribs which extend circumferentially of the chill and are arranged at different elevations respectively, and each rib being provided with a downwardly and

inwardly sloping seat-forming surface extending circumferentially of the chamber, and the upper of adjacent ribs being larger in dimension laterally of the chill and extending farther inwardly than the lower of the said ribs.

11. In a roll-casting mold, an upright chill having a circular chamber which extends from end to end of the chill and provided internally with ribs which extend circumferentially of the chill and are arranged at different elevations respectively, and each rib being provided with a downwardly and inwardly sloping seat-forming surface extending circumferentially of the chamber, and the upper of adjacent ribs being larger in dimensions laterally and longitudinally of the chill and extending farther inwardly than the lower of the said ribs.

12. In a roll-casting mold, the combination, with an upright chill having a circular chamber which extends from end to end of the chill, and provided with a hole which extends from the interior to the exterior of the chill, of an endwise shiftable bar or member engaging and movable endwise of the said hole and into the chamber and in its outer and normal position being arranged externally of the chamber, said endwise shiftable member extending a suitable distance outside of the chill and screw-threaded at the outer side of the chill; a nut mounted on the screw-threaded portion and forming an adjustable stop for limiting the inward movement of the said endwise shiftable member; means acting to actuate the said endwise shiftable member inwardly, and means for holding the said endwise shiftable member in its outer and normal position.

13. In a roll-casting mold, the combination, with an upright chill having a circular chamber which extends from end to end of the chill, said chill being provided with a hole which extends from the interior to the exterior of the chill, of an endwise shiftable bar or member engaging and movable endwise of the said hole and into the chamber and in its outer and normal position being arranged externally of the chamber, said endwise shiftable member extending a suitable distance outside of the chill, and means automatically acting to retain the said endwise shiftable member in its outer position, and means for shifting the said endwise shiftable member inwardly.

14. In a roll-casting mold, the combination, with an upright chill having a circular chamber which extends from end to end of the chill, said chill being provided with a hole which extends from the interior to the exterior of the chill, of an endwise shiftable bar or member engaging and movable endwise of the said hole and into the chamber and in its outer and normal position being arranged externally of the chamber, said

endwise shiftable member extending a suitable distance outside of the chill and provided externally of and a suitable distance from the chill with a laterally and outwardly

5 facing shoulder; a suitably supported lever overlapping the said shoulder and arranged to actuate the said endwise shiftable member inwardly; a spiral spring mounted and confined on the said endwise shiftable member and acting to retain the endwise shiftable member in its outer position, and means for locking the lever in the said outer position of the said endwise shiftable member.

15. In a roll-casting mold, the combination, 15 with an upright chill having a circular chamber which extends from end to end of the chill, said chill being provided with a hole which extends from the interior to the exterior of the chill, of an endwise shiftable bar 20 or member engaging and movable endwise of the said hole and into the chamber and in its outer and normal position being arranged externally of the chamber, said endwise shiftable member extending a suitable distance 25 outside of the chill and provided also externally with an outwardly facing shoulder; a lever overlapping the said shoulder and arranged to actuate the said endwise shiftable member inwardly; a stationary bracket supporting the lever and having an arm affording bearing to the said endwise shiftable member; a spiral spring mounted and confined on the said endwise shiftable member at the outer side of the said arm and acting 30 to retain the endwise shiftable member in its outer position, and means for locking the lever in the said outer position of the said endwise shiftable member.

16. In a roll-casting mold, the combination, 40 with an upright chill having a circular chamber which extends from end to end of the chill, and provided internally with suitably sloping seat-forming surfaces arranged at different elevations respectively, said chill being provided with a hole which extends 45 from the interior to the exterior of the chill, of an endwise shiftable bar or member engaging and movable endwise of the said hole and into the chamber and in its outer and 50 normal position being arranged externally of the chamber, and means whereby turning of the said endwise shiftable member is prevented.

17. In a roll-casting mold, a vertically arranged chill having its lower portion composed of superimposed rings which are provided internally with suitably sloping seat-forming surfaces extending circumferentially of the chill, said chill having its upper portion 60 composed of a comparatively long ring divided vertically into sections and provided internally with a plurality of suitably sloping seat-forming surfaces extending circumferentially of the chill, and the uppermost ring 65 of the first-mentioned or lower portion of the

chill being provided externally with lugs overlapping the exterior of the lower ends of the sections of the ring forming the upper portion of the chill, and wedges between the lugs and the said ring-sections.

18. In a roll-casting mold, a suitably supported upright chill provided at the upper end and externally with lugs which are spaced circumferentially of the chill and having a chamber extending from end to end of the chill, said chill being composed of superimposed rings; a lower mold-part or drag having a cavity which is provided with an inlet and communicates with the chill-chamber at the lower end of the chill; an upper 70 mold-part or cope provided with a chamber which communicates with the chill-chamber at the upper end of the chill, said cope comprising a casing which is provided externally with a laterally and outwardly projecting 75 flange which extends circumferentially of the cope and overhangs the aforesaid lugs; screws screwed into the said flange and extending through the flange into engagement with the upper end of the chill; bolts extending loosely 80 through and a suitable distance above the flange and loosely through the aforesaid lugs, which bolts are arranged with their heads under the lugs; nuts on the bolts above the flange, and washers interposed between the 85 flange and the nuts.

19. A roll-casting mold comprising a suitably supported upright chill; a suitably supported upper mold-part or cope arranged and adapted to be lowered within the chill; a lower mold-part or drag having a downwardly movable portion which has a cavity 100 communicating with the chill at the lower end of the chill, said drag comprising a stationary casing which is arranged externally 105 and extends circumferentially of the said movable portion of the drag and has a perforated bottom which is arranged a suitable distance below the cavity, the drag also having a runner-gate which extends through the said casing and communicates with the cavity, and the cavity-connecting portion of the runner-gate being adapted to lower with the aforesaid movable portion of the drag; means for interrupting continuity in the runner-gate between the stationary portion and downwardly movable portion of the runner-gate; a body of loose fluent material interposed between the aforesaid bottom and the aforesaid movable portion of the drag, and a 110 valve arranged to control the discharge of material through the said bottom.

20. A roll-casting mold comprising a suitably supported upright chill; a suitably supported upper mold-part or cope arranged and 115 adapted to be lowered within the chill; a lower mold-part or drag having a downwardly movable portion which has a cavity communicating with the chill at the lower end of the chill, said drag comprising a sta- 120 130

- tionary casing which is arranged externally and extends circumferentially of the said movable portion of the drag, and the drag also having a runner-gate which extends 5 through the casing and communicates with the cavity, and the cavity-connecting portion of the runner-gate being adapted to lower with the aforesaid movable portion of the drag, and a cut-off for interrupting continuity in the runner-gate between the downwardly movable portion and stationary portion of the runner-gate, said cut-off being movable downwardly with the aforesaid movable portion of the drag.
- 15 21. A roll-casting mold comprising a suitably supported upright chill; a suitably supported upper mold-part or cope arranged and adapted to be lowered within the chill; a lower mold-part or drag having a downwardly movable portion which has a cavity 20 communicating with the chill at the lower end of the chill, said drag comprising a stationary casing which is arranged externally of and extends circumferentially of the said movable portion of the drag, and the drag also having a runner-gate which extends 25 through the casing and communicates with the cavity, and the cavity-connecting portion of the runner-gate being adapted to lower with the aforesaid movable portion of the drag; a cut-off for interrupting continuity 30 in the runner-gate between the downwardly movable portion and stationary portion of the runner-gate, and a head arranged under and forming a support for the aforesaid downwardly movable portion of the drag, said head being supported as required 35 to render it capable of moving downwardly and bearing the cut-off.
- 40 22. A roll-casting mold comprising a suitably supported upright chill; a suitably supported upper mold-part or cope arranged and adapted to be lowered within the chill; a lower mold-part or drag having a downwardly movable portion provided with a cavity 45 which communicates with the chill at the lower end of the chill and has an inlet, and a head arranged under and forming a support for the said downwardly movable portion of the drag, said head being supported as required to render it capable of being lowered and provided with an arm projecting laterally and outwardly beyond the exterior of the drag.
- 50 23. A roll-casting mold comprising a suitably supported upright chill; a suitably supported upper mold-part or cope arranged and adapted to be lowered within the chill; a lower mold-part or drag having a downwardly movable portion provided with a cavity 55 which communicates with the chill at the lower end of the chill and has an inlet, said drag comprising a stationary casing extending circumferentially of and a suitable 60 distance below the said downwardly movable

portion of the drag; and a head arranged under and forming a support for the aforesaid movable portion of the drag and being contained within the aforesaid casing and supported as required to render it capable of being lowered, said head being provided with an upwardly projecting flange having a laterally and outwardly projecting arm extending externally of the said casing, and the casing being slotted vertically to accommodate 70 the location of the said arm during the descent of the head.

24. A roll-casting mold comprising a suitably supported upright chill; a suitably supported upper mold-part or cope arranged and adapted to be lowered within the chill; a lower mold-part or drag having a downwardly movable portion provided with a cavity which communicates with the chill at the lower end of the chill, said drag comprising a stationary casing extending circumferentially of the aforesaid movable portion of the drag and a runner-gate which extends through the casing and communicates with the drag-cavity, the cavity-connecting portion of the runner-gate being formed in and adapted to lower with the aforesaid movable portion of the drag; a head supporting the said movable portion of the drag and arranged within the aforesaid casing and supported as required to render it capable of being lowered, said head being provided with an upwardly projecting flange provided externally with a guideway, and a cut-off engaging the guideway and supported from the head, said cut-off being normally arranged externally of the aforesaid runner-gate but movable into a position obstructing continuity in the runner-gate at the outer end of the aforesaid downwardly movable portion of the runner-gate.

25. A roll-casting mold comprising a suitably supported upright chill; a suitably supported upper mold-part or cope; a lower mold-part or drag having a downwardly movable portion provided with a cavity which communicates with the chill at the lower end of the chill and has an inlet, said drag comprising a stationary casing extending circumferentially of the said movable portion of the drag and having a perforated bottom which is arranged a suitable distance below the drag-cavity; a body of fluent material between the said bottom and the aforesaid movable portion of the drag, and a rotary valve arranged to control the discharge of material through the said bottom.

26. A roll-casting mold comprising a suitably supported upright chill; a suitably supported upper mold-part or cope; a lower mold-part or drag having a downwardly movable portion provided with a cavity which communicates with the chill at the lower end of the chill and has an inlet, said drag comprising a stationary casing extending circumferentially of the said movable portion of the

- drag and having a perforated bottom which is arranged a suitable distance below the drag-cavity; a body of fluent material between the said bottom and the aforesaid movable portion of the drag; a valve arranged to control the discharge of material through the said bottom, and means whereby the valve may be operated from the upper end of the mold.
- 10 27. A roll-casting mold comprising a suitably supported upright chill; a suitably supported upper mold-part or cope; a lower mold-part or drag having a downwardly movable portion provided with a cavity which 15 communicates with the chill at the lower end of the chill and has an inlet, said drag comprising a stationary casing which has a perforated bottom arranged a suitable distance below the drag-cavity; a body of fluent material between the said bottom and the aforesaid movable portion of the drag; a valve supported from the said bottom and controlling the discharge of material through the said bottom, and lever-mechanism for operating the valve.
- 20 28. A roll-casting mold comprising a suitably supported upright chill; a suitably supported upper mold-part or cope; a lower mold-part or drag having a downwardly movable portion provided with a cavity which 25 communicates with the chill at the lower end of the chill and has an inlet, said drag comprising a stationary casing which has a bottom arranged a suitable distance below the said movable portion of the drag and provided with a centrally located hole and perforations spaced equidistantly from and circumferentially of the said hole; a rotary valve provided centrally with a cylindrical lug extending into the aforesaid centrally arranged hole, said valve having perforations which are in registry or out of registry with the first-mentioned perforations according as the valve is in its normal or closed position or 30 has been turned in its open position, and a body of fluent material between the aforesaid casing-bottom and the aforesaid movable portion of the drag.
- 25 29. A roll-casting mold comprising a suitably supported upright chill; a suitably supported upper mold-part or cope; a lower mold-part or drag having a downwardly movable portion provided with a cavity which 35 communicates with the chill at the lower end of the chill and has an inlet, said drag comprising a stationary casing which has a bottom arranged a suitable distance below the drag-cavity; a body of fluent material between the said bottom and the aforesaid movable portion of the drag; a valve arranged over the aforesaid bottom and provided on its under side and centrally with a cylindrical lug depending into the aforesaid centrally arranged hole, said valve
- having perforations which are in registry or out of registry with the first-mentioned perforations according as the valve is in its normal or closed position or has been turned into its open position, and a body of fluent material between the aforesaid casing-bottom and the aforesaid movable portion of the drag and filling the space formed around the conical valve.
- 30 30. A roll-casting mold comprising a suitably supported upright chill; a suitably supported upper mold-part or cope; a lower mold-part or drag having a downwardly movable portion provided with a cavity which 35 communicates with the chill at the lower end of the chill and has an inlet, said drag comprising a stationary casing having a perforated bottom arranged a suitable distance below the said movable portion of the drag; a body of fluent material interposed between the said movable portion of the drag and the said bottom; a valve for controlling the discharge of material through the said bottom-means for operating the valve, and means whereby the discharge of material through the said bottom is indicated externally of the drag.
- 35 31. A roll-casting mold comprising a suitably supported upright chill; a suitably supported upper mold-part or cope; a lower mold-part or drag having a downwardly movable portion provided with a cavity which 40 communicates with the chill at the lower end of the chill and has an inlet, said drag comprising a stationary casing which has a perforated bottom arranged a suitable distance below the drag-cavity; a body of fluent material between the said bottom and the aforesaid movable portion of the drag; means for controlling the discharge of material through the perforated bottom, and means whereby the discharge of material through the said bottom is indicated externally of the drag and at an elevation above the said bottom.
- 40 32. A roll-casting mold comprising a suitably supported upright chill; a suitably supported upper mold-part or cope; a lower mold-part or drag having a downwardly movable portion provided with a cavity which 45 communicates with the chill at the lower end of the chill and has an inlet, said drag comprising a stationary casing which has a perforated bottom arranged a suitable distance below the drag-cavity; a body of fluent material between the said bottom and the aforesaid movable portion of the drag; means for controlling the discharge of material through the perforated bottom; means whereby the descent of the said movable portion of the drag is mechanically indicated externally of the aforesaid casing, and means whereby the discharge of material through the aforesaid perforated bottom is indicated externally of the mold.

33. A roll-casting mold comprising a suitably supported upright chill; a suitably supported upper mold-part or cope; a lower mold-part or drag having a downwardly movable portion provided with a cavity which communicates with the chill at the lower end of the chill and has an inlet, said drag comprising a stationary casing which has a perforated bottom arranged a suitable distance below the drag-cavity; a body of loose fluent material between the said bottom and the aforesaid movable portion of the drag; means for controlling the discharge of material through the perforated bottom; a receptacle arranged under the bottom and in position to receive material discharged through the bottom; a suitably supported lever supporting the receptacle, and an upright rod arranged at one side of the mold and operatively connected with the lever.

34. A roll-casting mold comprising a suitably supported upright chill; a suitably supported upper mold-part or cope; a lower mold-part or drag having a downwardly movable portion provided with a cavity which communicates with the chill at the lower end of the chill and has an inlet, said drag comprising a stationary casing which has a perforated bottom arranged a suitable distance below the drag-cavity; a body of fluent material between the said bottom and the aforesaid movable portion of the drag; means for controlling the discharge of material through the perforated bottom; a receptacle arranged under the bottom and in position to receive material discharged through the said bottom, said receptacle being provided with two trunnions arranged at opposite sides respectively of the receptacle and in line endwise; a suitably supported lever arranged under the receptacle and provided at one side of its fulcrum with upwardly projecting arms affording bearing to the aforesaid trunnions, and a laterally supported upright rod operatively connecting with the lever at the other side of the fulcrum and extending to the upper end of the mold.

35. A roll-casting mold comprising a suit-

ably supported upright chill; a suitably supported upper mold-part or cope; a lower mold-part or drag having a downwardly movable portion provided with a cavity which communicates with the chill and has an inlet, said cavity being formed in and by two superimposed bodies of molding sand; a ring surrounding and supporting the upper of the said superimposed bodies; a head arranged under the lower of the said superimposed bodies and supported as required to render it capable of being lowered; and means for locking the said ring in its upper position.

36. A roll-casting mold comprising a suitably supported upper mold-part or cope; a lower mold-part or drag having a downwardly movable portion provided with a cavity which communicates with the chill at the lower end of the chill and has an inlet, said drag comprising a stationary casing, and an upright chill interposed between the drag and the cope and having a chamber extending from end to end of the chill and communicating at its lower end with the drag-cavity, said chill being provided internally with downwardly and inwardly sloping seat-forming surfaces extending circumferentially of the chill and arranged at different elevations respectively, and that portion of the chill which is provided with the lowermost of the aforesaid seat-forming surfaces being integral with the adjacent portion of the aforesaid drag-casing.

37. In a roll-casting mold, an upright chill having a circular chamber and provided internally with seats arranged at different elevations respectively and extending circumferentially of the chamber, and the upper of adjacent seats extending farther inwardly than the lower of the said seats.

In testimony whereof, I sign the foregoing specification, in the presence of two witnesses.

RALPH H. WEST.
